CLAIM

The ornamental design for a soother, as shown and described.

DESCRIPTION

1.-2. Soother

1.1 is a perspective view showing the soother of my design;

1.2 is a front elevational view thereof;

1.3 is a rear elevational view thereof;

1.4 is a left side elevational view thereof;

1.5 is a right side elevational view thereof;

1.6 is a top plan view thereof; and

1.7 is a bottom plan view thereof.

2.1 is a perspective view showing the soother of my design;

2.2 is a front elevational view thereof;

2.3 is a rear elevational view thereof;

2.4 is a left side elevational view thereof;

2.5 is a right side elevational view thereof;

2.6 is a top plan view thereof; and

2.7 is a bottom plan view thereof.
